UNITED STATES PATENT OFFICE.

JAMES CLIFTON, JAMES ROBINSON, AND JOHN SPENCER, OF LONDON, ENGLAND.

TIME SWITCH.

Application filed May 5, 1922, Serial No. 558,619, and in Great Britain February 13, 1922.

This invention relates to time switches, particularly suitable for shop-window lights, light-signs, or other purposes where electric current is required for a predetermined period of time.

An object of the invention is to provide a device whereby the mechanism can be set to switch on, and switch off, at predetermined and selected times, so rendering the service of an attendant requisite only to set the mechanism, and which can be done at any time during the day.

According to the present invention there is provided for automatically controlling the opening and closing of a switch in an electric circuit, a clock mechanism combined with a revolving tappet carrier driven thereby to rotate at the same speed as the hour hand of the clock; at least two tappets adjustably mounted on the said carrier, means for holding the tappets in their adjusted position, and a movable trip-lever so disposed in the path of the tappets that as they are moved by the carrier the said trip-lever will be engaged and moved in succession by each of them. The purpose of so engaging the trip-lever with the tappets is that movement of the said lever by one tappet will cause an abutment face on the said lever to be disengaged from, and so release a rotatable or partially rotatable escapement member, pawl or arm, to which the rod operating the electric switch is pivoted.

In one form of the invention, the switch-operating mechanism comprises, in combination, an escapement in the form of a partially rotating member having abutments arranged on opposite sides of its axis of rotation, means (for example a coiled spring), always tending to rotate said member in one direction, a switch operatively connected with said member, and an abutment face formed on the trip-lever near the axis of the same and normally engaging an abutment on the escapement. The tappet contact face of the trip-lever which is at a greater distance from the axis of the said lever is disposed in the path of the tappets.

And in order that the invention may be readily understood we will now describe it fully with reference to the accompanying drawings, wherein:

Figure 1 is an elevation of the improved time switch as seen from the back when the case is opened, the dotted circular line showing the position which the electric switch

would occupy when the case is closed, said switch being situated in the back portion of the case.

Figure 2 is a plan of Fig. 1, the back being closed.

Figure 3 is a side elevation of Fig. 1, looking from the right, also with the back of the case closed.

Figures 4 and 5 are detail views of the partially rotatable escapement member and the trip-lever respectively.

Figure 6 is a similar view to Fig. 1 of an apparatus adapted to operate over a period of time exceeding twenty-four hours.

Figures 7 and 8 are details of certain parts illustrated in Figure 6.

The same letters of reference indicate like parts throughout the drawings.

Referring to Figures 1 to 5, which show the mechanism intended to operate for a period of twenty-four hours only, the parts of the clock mechanism which are illustrated, are simply those necessary for the understanding of the invention. The arbor d of the hour hand or the hour pinion d^1 of the clock is geared with the pinion d^3 through an intermediate pinion d^2 so that the pinions d^1 , d^3 , rotate in the same direction with a gear ratio of 1 to 1. Fast on the spindle of the pinion d^3 is a tappet carrier e , in the form of a disc having a ring of teeth or analogous means on its face, into which engage the tappets g and h on the carrier e , and hereinafter fully referred to.

On the spindle of the pinion d^3 two tappets g and h are loosely and radially applied and the angular position of these tappets can be adjusted in relation to the carrier e after which they maintain engagement with the teeth f by means of a coiled spring d^4 (or springs) mounted on the arbor of the carrier e and the pinion d^3 . The tappet h is slightly longer than the tappet g for a purpose which will be presently explained.

The carrier e is marked with figures corresponding to the hours of the clock dial. A trip-lever i , pivotally mounted at i^1 , is normally held in the position illustrated in full lines in Fig. 1, by a counter-balance tension spring l . On the trip-lever i is formed an abutment face k which is normally held in the path of an escapement member, pawl, or arm a , rotatably mounted on a spindle a^1 , which is connected to one end of a coiled spring r , as shown in Fig. 1, the other end of which is anchored to a fixed part of the

frame of the mechanism. A setting handle a^2 is secured to the partially rotatable escapement member a , and on a crank-pin j^1 extending from said escapement member a is pivoted one end of a switch-rod j having a controlled vertical action, and detachably engaged by its forked lower extremity j with the tumbler v of the tumbler-switch V . The object of so engaging the forked extremity j with the tumbler v is to enable the front portion of the case containing the clock to be swung open away from the back on its hinge in order to wind and set the clock and switch-operating mechanism without causing the switch V to be actuated while so doing.

The operation of the apparatus is as follows:—The spring r connected with the spindle a^1 is wound by rotating the member, 20 pawl or arm a , by means of the handle a^2 in a clockwise direction, as viewed in Fig. 1, so that a face b , comprising one of the abutment faces hereinbefore referred to, at one extremity of the member a , is engaged with 25 the abutment face k of the trip-lever i . This is effected by two motions of the handle a^2 when the member is in its unwound or rest position; the handle a^2 is partially rotated, first in a clockwise direction which brings 30 the rear of the abutment face c into contact with the uppermost portion of the abutment face k , the motion being continued causing the trip-lever and the abutment face k to be depressed until the abutment-face c has 35 passed and allows the trip-lever and abutment-face k to be returned by the agency of the counter-balance spring l , when, by a further motion of the handle a^2 in the same direction, the abutment-face b is moved until 40 the said abutment passes the abutment-face k with the same action as in the case of abutment-face c , and the trip-lever and the abutment-face k have again returned, as previously described, thus retaining the member 45 a .

In the foregoing action it is seen that the member a and the trip-lever i with its abutment-face k have virtually the action of a click and ratchet during winding. The 50 tappet g is then set in relation with the hour-markings of the disc e to the time at which it is required to close the switch V , and the tappet h is set to the hour at which the switch is to be opened again. The trip-lever i will be in the position shown in full lines. As the disc e rotates, the tappet g , at the hour for which it is set, engages the end i^2 of the trip-lever i and depresses it sufficiently far so as to disengage the abutment-face k from the abutment-face b . The member a is then rotated under the action of its spring until the abutment-face c is arrested by the abutment-face k , and when this occurs the switch will close 65 with a rapid action. At the selected hour,

the tappet h then engages the end i^2 of the trip-lever i , and depresses it still further so as to release the abutment-face k from the abutment-face c of the member a , whereupon the latter will be again partially rotated by its spring for another part revolution in the same direction, thus moving the switch-rod j to open the switch also with a rapid action. The foregoing action having taken place, the clock still working, the switch-operating mechanism will not again function until re-set or re-wound.

In the construction illustrated in Figures 6, 7 and 8, the mechanism, suitable, say, for an eight or more day clock, is similar to that before described, in that a disc e , is provided as before, with tappets g and h . This disc, however, is geared to the hour pinion d^1 so that the gear ratio between them is 1 to 2. Thus the disc e rotates once only in twenty-four hours. The extremity i^2 of the trip-lever i , being the upper face, is engaged by the tappet g , and the other face of the extremity i^3 is so shaped as to be engaged by a lateral projection on the extremity of the tappet h so that the trip-lever will be returned by its engagement with the tappet h . The spring r for the member a is of greater length than that previously described, so that by one winding of the spring the member a will be rotated many times. This member has an abutment-face on one side only of its axis of rotation, and engages with stops on the escapement member n , which stops are constituted by pins n^1 , n^2 , projecting from a slider n , connected by a link O with the trip-lever i . This link can, however, be dispensed with, without in any way affecting the action of the slide. The member a is connected by a crank p , as before, with the switch-rod j . The slider n is notched as shown, so as to be engaged by a spring n^3 , and thereby steadied in either of its limiting positions of movement under the action of the trip-lever i .

Instead of guide-slots and guide-pins we may employ guide links so as to impart a straight up and down motion to the escapement member n .

It will be readily understood, therefore, that when the trip-lever is depressed by engagement with the detent g , the slider is moved downwardly to disengage the stop n^1 from the member a , also to move the stop n^2 at the same time into the path of the member a , as it moves the desired portion of a revolution allowed for, to close the switch under the action of its spring r . When the trip-lever i is returned by engagement with the detent h , the stop n^2 is freed from engagement with the member a and the stop n^1 is moved into the path of the latter to engage it when it has moved another portion of a revolution as arranged for, and thus opening the switch V .

It will be seen from the above disclosure that in both of the devices described the tappets are rotatably movable relatively to the teeth *f* of the carrier *e* to obtain the desired adjustment of said tappets, so that the tappets act directly on the lever *i* and the switch *V* is turned on or off as the case may be, by a single movement of the escapement member which we prefer to call a one-beat escapement action.

In both arrangements herein described, the clock mechanism, the switch mechanism, and the electric switch, are all contained in a hinged case, the back portion of which contains the switch *V*, which is permanently fixed therein, and which portion is itself fixed to a wall when in use. The front portion of the case contains the switch-operating mechanism and the clock, this portion swinging outwardly from the back and so disconnecting the switch from the switch-rod *j* and its operating mechanism when winding and setting the clock and switch-operating mechanism. It is, however, possible to operate the switch *V* by hand owing to the swinging out of the front half of the case.

Having now described our said invention what we claim is:—

1. A device of the character described, comprising a switch and means for controlling the opening and closing thereof, said means consisting of a clock mechanism, a tappet carrier driven by said clock mechanism and carrying a ring of teeth, spring controlled tappets mounted on the carrier, said tappets being adapted to be moved freely over said teeth and to take up a definite and positive time position when the movement ceases; a spring-controlled pivotally mounted trip-lever having an abutment face at its axis end, and a tappet abutment face at its free end disposed in the path of said tappets and adapted to be in turn deflected downwardly by each of said tappets; a partially rotatable escapement member having two contact faces in the path of which the abutment face at the axis of the trip lever is normally held, one of the abutment faces being at a greater distance from the axis than the other abutment face; permanently fixed means for winding the said escapement member, an electric switch, a switch-rod having a controlled vertical movement and pivoted at one end to the escapement member and at the other end detachably engaging the electric switch substantially as herein described.
2. A device of the character described, comprising a switch and means for opening and closing the switch, said means consisting of clock mechanism, a tappet carrier regularly rotatable by said clock mechanism and having a ring of teeth, spring controlled tappets mounted on the carrier and adapted to be moved freely over said teeth and be adjusted to a definite and positive time position when the movement ceases, a spring-controlled, pivotally mounted trip lever having an abutment face at its axis end and a tappet abutment face at its free end disposed in the path of movement of said tappets and adapted to be in turn deflected downwardly by each of the tappets, a switch operating device having a controlled vertical movement, and an escapement means cooperating with the said switch operating device and the said trip lever, the switch operating device having means to detachably engage the means for controlling the opening and closing of the switch, the escapement means having a part to engage the switch operating device and to automatically shift the position of the latter in accordance with the actuation of the trip lever by the tappets.
3. A device of the character described, comprising a switch and means for controlling the opening and closing thereof, said means consisting of a clock mechanism, a tappet carrier driven by said clock mechanism and carrying a ring of teeth, spring controlled tappets mounted on the carrier, said tappets being adapted to be moved freely over said teeth and to take up a definite and positive time position when the movement ceases; a spring-controlled pivotally mounted trip-lever having an abutment face at its axis end, and a tappet abutment face at its free end disposed in the path of said tappets and adapted to be in turn deflected downwardly by each of said tappets; a partially rotatable escapement member having two contact faces in the path of which the abutment face is normally held, one of the abutment faces being at a greater distance from the axis than the other abutment face; permanently fixed means for winding the said escapement member, an electric switch, a switch-rod having a controlled vertical movement pivoted at one end to the escapement member and at the other end detachably engaging the electric switch, said mechanism being arranged in a casing comprising hinged parts, the switch and controlling mechanism therefor being secured respectively on one of the hinged parts, the other on the other hinged part of the casing, substantially as herein described.
4. A device of the character described, comprising a switch and means for controlling the opening and closing thereof, said means consisting of a clock mechanism, a tappet carrier driven by said clock mechanism and carrying a ring of teeth, spring controlled tappets mounted on the carrier, said tappets being adapted to be moved freely over said teeth and to take up a definite and positive time position when the movement ceases; a spring-controlled pivotally mounted trip-lever having an abutment

face at its free end disposed in the path of said tappets and adapted to be in turn deflected downwardly by each of said tappets; a partially rotatable escapement member having two contact faces in the path of which the abutment face at the axis of the trip lever is normally held, one of the abutment faces being at a greater distance from the axis than the other abutment face; permanently fixed means for winding the said escapement member, an electric switch, a switch-rod having a controlled vertical movement pivoted at one end to the escapement member and at the other end detachably engaging the electric switch, a fixed handle on the escapement member, whereby said member can be ratcheted in a reverse direction and act with a click and ratchet action in conjunction with the trip-lever 20 and its abutment face.

5. In a device of the character described, a switch, an escapement member connected therewith, a spring-controlled rocking member for releasing the escapement member, 25 clock driven means having a ring of teeth rigid therewith and tappets of unequal length rotatably mounted thereon for operating said spring controlled rocking member, and a centrally operating spring normally 30 pressing said tappets into engagement with said teeth.

6. In a device of the character described, a switch, a spring actuated escapement having a depending lever operatively connected 35 with said switch, a trip-lever pivoted at one end for operating said escapement and comprising a projecting arm and a clock driven member having tappets of unequal length rotatably mounted thereon and adapted to 40 act directly on free end of said projecting

arm of the trip-lever to effect different degrees of movement of said trip lever to cause the lever to operate said escapement.

7. In a device of the character described, a clock mechanism, a tappet carrier driven by said mechanism and having a ring of teeth on one face, spring-controlled tappets of unequal length movably mounted on said tappet carrier, a spring controlled pivotally mounted trip-lever having an abutment face 45 at its axis end and a contact face disposed in the path of said tappets, a rotatable escapement member having two contact faces, means maintaining the abutment face of the trip-lever normally in the path of the 50 contact faces of said escapement member, a switch rod pivoted to said escapement member and adapted to engage by its opposite end an electric switch.

8. In a device of the character described, a clock mechanism, a tappet carrier driven by the clock mechanism and having a ring of teeth on one face, spring-controlled tappets of unequal length movably mounted on 55 said tappet carrier, a spring controlled pivotally mounted trip member having an abutment disposed in the path of said tappets, a rotatable escapement member, one of said members having two contact faces, means 60 maintaining the abutment face of the trip-lever normally in the path of the contact faces of said escapement member, a switch rod pivoted to said escapement member and adapted to engage by its opposite end an 65 electric switch.

In witness whereof, we have hereunto signed our names.

JAMES CLIFTON.
JAMES ROBINSON.
JOHN SPENCER.
